UNITED STATES PATENT OFFICE.

GEORGE TAYLOR, OF JERSEY CITY, NEW JERSEY, ASSIGNOR TO THE J. L. MOTT IRON WORKS, OF NEW YORK, N. Y.

NEEDLE OR SPRAY BATH.

SPECIFICATION forming part of Letters Patent No. 335,785, dated February 9, 1886.

Application filed August 17, 1885. Serial No. 174,542. (No model.)

To all whom it may concern:

Be it known that I, GEORGE TAYLOR, of Jersey City, in the county of Hudson and State of New Jersey, have invented a new and useful Improvement in Needle or Spray Baths; 5 and the following is declared to be a description of the same.

Needle or spray baths have been used before in connection with what are known as 10 "Turkish" and "Russian" baths, the special feature of said needle or spray baths being to throw upon the person of the bather fine needle-like streams of hot, cold or tepid water. Baths of this kind are provided with 15 a "shower" overhead, "liver-sprays" to direct the water upon the sides of the bather, and a "douche" or fountain-spray to direct the water upward.

My invention relates to a needle or spray 20 bath of this general character; and the same consists in the improvements hereinafter described, whereby simplicity in construction and efficiency in operation are attained.

In my improved needle or spray bath the 25 bather can be sprayed all over without the necessity of changing his position; and the cocks for opening and shutting the water supply pipes are made in such a manner that the cold-water supply is always open and the 30 hot-water supply is limited, in order that the quantity passing into the mixing-column may never be too great; hence there is no risk of the person being scalded, and the hot and cold water are controlled so that the spray may 35 be of any desired temperature. A thermometer is connected with the apparatus to indicate the temperature of the water as it passes to any point of the apparatus, and there are valves to regulate the passage of the water to 40 different parts of the apparatus.

In the drawings, Figure 1 is an elevation of the apparatus complete, portions of the front tubes being removed. Fig. 2 is a plan below the line $\alpha\alpha$. Fig. 3 is a vertical section of the 45 rose and jet tube for the douche. Fig. 4 is a sectional plan of one rose and cock for the liver-sprays; and Fig. 5 is a sectional plan of the hot and cold water cocks; and Fig. 6 is a vertical section of the mixing-column, showing 50 the thermometer and bulb.

The apparatus is to stand upon a suitable

base, A, which may be in the form of a pan, to which a waste-pipe is connected, and there is an inclosing-case, B, of sheet metal or other material, to surround the apparatus on three 55 sides, and there may be a cover, C, and a door may also be provided, if desired. I make use of four columns, E E F F, supported at the bottom by the base A, and connected at the top ends by T's and bends with the pipes G, 60 which form a top frame that opens into said columns, and connected with this top frame is the supply-pipe H, having a cock or valve, I, by which the force of the water is regulated. These columns E E and F F are perforated 65 with vertical ranges of fine holes, through which the water issues toward the person when standing centrally between the columns.

K is the pipe through which hot water is supplied, and L is the pipe through which the 70 cold water is supplied. These pass to the respective cocks, M N, in any desired manner, and between these cocks M N and the supply-pipe H' is the four-way coupling P.

I make use of a thermometer at Q, the tube 75 and scale of which are outside the mixing-column H'; but the bulb of the thermometer is within such mixing-column, so that said thermometer indicates the temperature of the water as the same is mixed in the column H'. 80 This enables the party who is taking a bath to ascertain the temperature of the water and not to use water that is too hot and liable to injure the person, or too cold and liable to produce a chill.

The cold-water valve N is to be made so that the cold water cannot be entirely shut off. This may be done by notching the edges of the valve; but in Fig. 5 I have shown a hole, n, 85 as passing through the partition of the valve; hence the water can always pass through the said hole, and the volume can be increased by opening the valve. The hot-water valve M is to be of small dimensions, and it is preferable to make use of a tapering base to the 90 valve, passing through the seat, as seen in Fig. 5, so that the supply of hot water will be opened very gradually, and a risk of scalding be avoided.

At the lower part of the mixing-column H' 100 is a cock, R, and a pipe, R', that descends to the horizontal pipe R² and rose R³ of the

douche, and it is preferable to terminate the pipe R^2 as a vertical jet-tube, R^4 , around the outside of which the base of the rose R^3 is screwed. This allows for the use of a jet-douche when the rose is removed.

From the lower part of the coupling P branch pipes S S pass off laterally, and they may be bent so as to pass around the outsides of the columns F F, or they may pass across 10 through the columns, and the tubes S S terminate about midway between the columns E F with tapering plugs S' and surrounding barrels S², forming cocks, and the pipe and rose S³ upon each barrel S² forms a handle, by 15 which the barrel S² can be turned to open the cock for the water to pass through the same, and the rose may be directed toward the person either horizontally or at an upward or downward inclination, the water being shut 20 off when the rose is turned vertically up or down.

From the supply-pipe H', below the cock I, there is a branch pipe, U, extending up to the shower U'. This pipe is also bent, so 25 as to pass around the horizontal pipe G, or through it, if desirable, and in this pipe at a convenient position is the cock U². It is now to be understood that the cocks M N admit the supply of water to the whole apparatus, so that the temperature may be 30 regulated by these cocks, and either hot, cold, or tepid water will be supplied, according to the amount which the respective cocks are opened, and these cocks do not require to 35 be moved, except for changing the temperature. The cock I regulates the quantity of water passing through the pipe H, frame G, and perforated columns E E and F F, so that more or less water may be sprayed upon the 40 person from the columns E E and F F. The cock R regulates the quantity of water discharged through the douche-rose R³ or jet R⁴. The cock U² regulates quantity of water discharged by the shower, and the liver-spray 45 roses S³ are self-acting to the extent that when turned into the position for use against the person the supply of water is simultaneously turned on. My apparatus is therefore very cheap; but it is more efficient and reliable 50 than the devices heretofore made.

I claim as my invention—

1. The combination, in a needle or spray bath, of the hot and cold water pipes K L, the coupling or branch pipe P, connecting the same, the hot and cold water cocks M N in the hot and cold water pipes, the mixing-column H' above the coupling P, the cock I and supply-pipe H, the vertical perforated columns

E E F F, and the pipes G, forming a top frame and connecting the columns to the supply-pipe 60 H, substantially as specified.

2. The combination, in a needle and spray bath, of the hot and cold water pipes K L, the coupling or branch pipe P, connecting the same, the hot and cold water cocks M N in the hot and cold water pipes, the mixing-column H' above the coupling P, and a thermometer, Q, upon the surface of the column H', its stem passing through the column with the bulb inside, the cock I and supply-pipe H, the vertical perforated columns E E F F, and the pipes G, forming a top frame and connecting the columns to the supply-pipe H, substantially as specified.

3. The combination, in a needle-spray bath, 75 of the hot and cold water pipes K L, the coupling or branch pipe P, connecting the same, the hot and cold water cocks M N in the hot and cold water pipes, the mixing-column H' above the coupling P, the cock I and supply-pipe H, the vertical perforated columns E E F F, the pipes G, forming a top frame and connecting the columns to the supply-pipe H, and the lateral pipes S, connected to the coupling P, and extending out horizontally, the plugs S', 80 and the movable barrels S², and spray-roses S³, 85 substantially as specified.

4. The combination, in a needle-spray bath, 90 of the hot and cold water pipes K L, the coupling or branch pipe P, connecting the same, the hot and cold water cocks M N in the hot and cold water pipes, the mixing-column H' above the coupling P, the cock I and supply-pipe H, the vertical perforated columns E E F F, the pipes G, forming a top frame and connecting 95 the columns to the supply-pipe H, and the cock R, descending pipe R', pipe R², and douche, substantially as specified.

5. The combination, in a needle or spray 100 bath, of the hot and cold water pipes K L, the coupling or branch pipe P connecting the same, the hot and cold water cocks M N in the hot and cold water pipes, the mixing-column H' above the coupling P, the cock I and supply-pipe H, the vertical perforated columns 105 E E F F, the pipes G, forming a top frame and connecting the columns to the supply-pipe H, and the branch pipe U, extending upwardly from the mixing-column H', the cock U², and shower U', substantially as specified.

Signed by me this 11th day of August, A. D. 1885.

GEORGE TAYLOR.
